UNITED STATES PATENT OFFICE.

HARRY SAWYER, OF MUSKEGON, MICHIGAN, ASSIGNOR TO SHAW ELECTRIC CRANE COMPANY, OF MUSKEGON, MICHIGAN, A CORPORATION OF MICHIGAN.

OPERATING MECHANISM FOR HOISTING APPARATUS.

1,251,289.

Specification of Letters Patent.

Patented Dec. 25, 1917.

Application filed July 12, 1916. Serial No. 108,831.

To all whom it may concern:

Be it known that I, HARRY SAWYER, a citizen of the United States, residing at Muskegon, in the county of Muskegon, State 5 of Michigan, have made a certain new and useful Invention in Operating Mechanism for Hoisting Apparatus, of which the following is a specification.

This invention relates to operating mechanism 10 for hoisting apparatus.

The object of the invention is to provide an operating mechanism for hoisting apparatus which is simple in structure, economical to manufacture and efficient in operation.

A further object of the invention is to provide an operating mechanism for hoisting apparatus including a hoisting drum and a racking drum and operating motors 20 therefor with an intermediate planetary gearing system operating to drive the drums in the same direction, and with a desirable gear ratio between the hoisting motor and drum and, wherein, the drums are driven 25 at the same peripheral speed, whether the drums are of the same or of unequal diameters.

Other objects of the invention will appear more fully hereinafter.

30 The invention consists substantially in the construction, combination, location, and relative arrangement of parts, all as will be more fully hereinafter set forth, as shown in the accompanying drawings, and finally 35 pointed out in the appended claims.

Referring to the drawings:

Figure 1 is a view in top plan showing an operating mechanism for hoisting apparatus embodying the principles of my invention.

40 Fig. 2 is a broken view in section on the line 2, 2, Fig. 3, looking in the direction of the arrows.

Fig. 3 is a broken view in transverse section on the line 3, 3, Fig. 2, looking in the direction of the arrows.

The same part is designated by the same reference numeral wherever it occurs throughout the several views.

50 It is among the special purposes of my invention to provide a hoisting apparatus

and operating mechanism therefor, which avoids the objectionable friction developed by hoisting or controlling ropes or cables operating through running sheaves and 55 wherein the hoisting rope is wound up or paid out coincidently with the travel of the trolley as the same is racked in one direction or the other. In accordance with my invention I provide a suitable motor bed or 60 frame 1, upon which are provided journals 2, 3, for the main operating shaft 4. Suitably geared to shaft 4, through the intermeshing gears 10 is a racking drum 5. A hoist drum 6 is geared to be driven through 65 intermeshing gears 11, one of which is carried by a sleeve journaled to revolve upon said shaft 4. A planetary gear system is inclosed within a casing 7, and is operated by motors 12, 13, the motor 12 being the 70 rack drum operating motor and the motor 13, being the hoist drum operating motor, although, as will be hereinafter explained, the operation of the rack motor 12, rotates not only the rack drum but also the hoist 75 drum.

Suitably connected to rotate with shaft 4, and to be engaged and driven by a rack motor 12, is a gear wheel 8. Connected to rotate with spur gear 8 is a spur gear 9. A 80 convenient arrangement is shown, to which, however, my invention is not to be limited or restricted, wherein the hub of spur gear 9 is keyed to shaft 4, and gear 8 is keyed upon the hub of gear 9. Loosely sleeved upon shaft 4 is a wheel 14, carrying an annular internally toothed gear 15, disposed in juxtaposition to the spur gear 9. The hub of wheel 14 carries one member of the intermeshing gears 11, through which the hoist 90 drum 6 is operated. Loosely sleeved upon shaft 4 is a spur gear 16, arranged to be driven by the hoisting motor 13. Carried by spur gear 16 are studs 17, arranged in pairs. Pinions 18 are journaled upon the studs 17, 95 each pair of pinions intermeshing with each other, one of said pinions of each pair meshing with spur gear 9, and the other of said pinions meshing with the juxtaposed annular gear 15.

With the construction above described it will be seen that when the rack motor 12, is

operated, assuming the hoist motor to be out of operation, the rack drum 5 will be driven through the gear 8 and shaft 4, to which said gear is connected and the intermeshing gears 10 intermediate the shaft 4, and the rack drum. At the same time the gear 9 is also rotated, thereby axially rotating that member of each pair of pinions which meshes therewith, and through the associated pinions of each pair rotations are at the same time imparted to the annular gear 15, and hence through wheel 14, and its hub and the intermeshing gears 11, effecting a coincident rotation of the hoist drum 6. When, however, the rack motor is out of operation and the hoist motor is operated, gear 16 is rotated thereby carrying the pinions 18 around with it. This action through the intermeshing of one member of each pair of pinions with the gear 9, imparts axial rotation to said pinions and hence to the annular gear 15 and its carrying wheel 14, and hence to the hoisting drum through gears 11, without, however, rotating the rack drum. Since the hoist drum is operated by both motors it is required to wind or unwind rope or cable for both the total hoist and the total rack movements, while the rack drum winds rope only for the rack movements. Therefore, while the drums 5, 6, may be made of the same diameter and the gear ratios of gearings 10 and 11, so proportioned as to give the same peripheral speeds to the drums 5, and 6, it will be found desirable to make the hoist drum of larger diameter in order to enable it to wind more rope than the rack drum. In any case it will be seen that the drums 5 and 6, are driven in the same direction and by suitably selecting the diameter of the drums and the gear ratios of gearing 10 and 11, said drums, whether of the same diameters or not, may be driven at the same peripheral speeds.

Various changes in details of construction and arrangement will readily occur to persons skilled in the art and still fall within the spirit and scope of my invention. I do not desire, therefore, to be limited or restricted to the exact details shown and described.

Having now set forth the object and nature of my invention, what I claim as new

and useful, and of my own invention, and desire to secure by Letters Patent, is,—

1. In an operating mechanism for hoisting apparatus, a main shaft, a rack drum and a hoist drum, a sleeve loosely journaled on said shaft, gearing intermediate said shaft and rack drum, gearing intermediate said sleeve and hoist drum, means for coincidently rotating said shaft and sleeve and independent means for rotating said sleeve. 55

2. In an operating mechanism for hoisting apparatus, a main shaft, a rack drum and a hoist drum, a sleeve loosely journaled on said shaft, gearing intermediate said shaft and rack drum, gearing intermediate said sleeve and hoist drum, a motor, gearing actuated by said motor for simultaneously rotating said shaft and sleeve and an independent operating motor to rotate said sleeve. 60

3. In an operating mechanism for hoisting apparatus, a rack drum and a hoist drum, a main operating shaft, gearing intermediate said shaft and rack drum, a sleeve journaled on said shaft and geared to said hoist drum, an internally toothed annular gear carried by said sleeve, a spur gear rotating with said shaft, a spur gear loosely mounted on said shaft and carrying planetary gears to coöperate with said annular and spur gears, and motors respectively geared to said shaft and loosely mounted spur gear. 75

4. The combination with rack and hoist drums and motors and a main shaft, of a spur gear connected to said shaft to rotate therewith, said spur gear being driven by said rack motor, a juxtaposed internally toothed annular gear, intermeshing pinions respectively meshed with said spur and annular gears, a gear wheel carrying said pinions and geared to said hoist motor, gear connections intermediate said annular gear and said hoist drum. 80

In testimony whereof I have hereunto set my hand, in the presence of the subscribing witnesses, on this 29th day of June, A. D. 1916.

HARRY SAWYER.
